MACHINE GUN AND AUTOMATIC SMALL
ARM OF THE GAS OPERATED TYPEArthur Joseph Palmer and Percy Reuben Higson,
Westminster, England, assignors to Vickers-
Armstrongs Limited, Westminster, England, a
British companyApplication July 6, 1933, Serial No. 679,156
In Great Britain August 25, 1932

8 Claims. (Cl. 42—3)

This invention relates to machine guns and automatic small arms of the gas operated type. It has heretofore been customary to stop the forward movement of the gas operated piston rod by means of a stop member inserted into or made integral with the gun casing, a shoulder on the piston rod bearing against this stop member to limit the forward movement of the piston rod. This stop member has heretofore had a face at right angles to the direction of movement of the piston rod and the shoulder on the piston rod has a similarly shaped face, and it is found in practice that with such a construction the piston rod is liable to rebound with consequent disadvantages. The chief object of the invention is to overcome this difficulty.

According to the invention the co-operating faces on the stop member and on the piston rod, instead of being at right angles to the direction of motion as mentioned above, are arranged at a suitable angle other than a right angle to the said direction of movement to produce a cushioning effect so that rebound of the piston rod is prevented or substantially reduced.

In order that the said invention may be clearly understood and readily carried into effect, the same will now be described more fully with reference to the accompanying drawing in which:—

Figure 1 is a side elevation of part of a machine gun made in accordance with the invention;

Figure 2 is a section on the line II—II in Figure 1, and

Figure 3 is a sectional view of the gun casing (omitting the piston rod) on the line III—III in Figure 1.

The gas operated piston rod A has at its upper part the abutment face A¹, and the stop member B has the co-operating face B¹. Each of the faces A¹, B¹, is part of a frusto-conical surface and is in the example shown at an angle of sixty degrees to the longitudinal axis of the piston rod. The faces also slope in a rearward direction, i. e. the upper or outer edges A² (remote from the axis of the piston rod) are nearer to the rear end of the gun than the lower or inner edges. A stop arrangement as above described will limit the forward movement of the piston rod without appreciable rebound.

The faces A¹, B¹, may slope forwardly, instead of rearwardly as described above.

The stop member B is in the form of a rivet inserted in the gun casing D and cut away to form the face B¹ as shown in Figure 3.

The stop member B may however be formed integrally with the gun casing D.

E indicates the usual spring for pressing the piston rod forwardly.

What we claim and desire to secure by Letters Patent of the United States is:—

1. A machine gun or automatic small arm of the gas operated type having a gas operated piston rod, an abutment on said piston rod, and a rigid stop member for co-operating with said abutment, the co-operating faces of the abutment and stop member being at an angle other than perpendicular to the direction of movement of the piston rod, for reducing rebound of the piston rod. 60

2. A machine gun or automatic small arm as in claim 1, wherein said faces are inclined with their outermost edges, remote from the axis of the piston rod, nearer to the rear end of the gun than their inner edges. 70

3. A machine gun or automatic small arm of the gas operated type having a gas operated piston rod, an abutment on said piston rod, and a rigid stop member for co-operating with said abutment, the co-operating faces of the abutment and stop member being at an angle of sixty degrees to the axis of the piston rod. 75

4. A machine gun or automatic small arm as in claim 1, wherein said faces are parts of frusto-conical surfaces. 80

5. A machine gun or automatic small arm as in claim 1, wherein the stop member is in the form of a rivet inserted in the gun casing and shaped to form an inclined stop face. 85

6. A machine gun or automatic small arm of the gas operated type having a gas operated piston rod, an abutment on said piston rod, and a rigid stop member for co-operating with said abutment, the abutment and stop member having co-operating faces at an angle other than perpendicular to the direction of movement of the piston suitable for reducing rebound of the piston rod and the inclination being such that the outermost edges of said faces are nearer to the rear end of the gun than their inner edges. 90

7. A machine gun or automatic small arm of the gas operated type having a gas operated piston rod, an abutment on said piston rod, and a stop member for operating with said abutment, the stop member being in the form of a rivet inserted in the gun casing and shaped between its ends to form a stop-face comprising part of a frusto-conical surface at an angle of sixty degrees to the axis of the piston rod with the outermost edge nearer to the rear end of the gun than its inner edge and the co-operating face 110

of the abutment being of similar shape and inclination.

8. A machine gun or automatic small arm of the gas operated type having a gas operated piston rod, a spring acting on said piston rod to move the rod forwardly, an abutment on said piston rod, and a rigid stop member for co-operating with said abutment to limit the extent of

movement of said piston rod under the action of said spring, the co-operating faces of the abutment and rigid stop member being at an angle other than perpendicular to the direction of movement of the piston rod for reducing rebound of the piston rod.

ARTHUR JOSEPH PALMER.
PERCY REUBEN HIGSON.
